US0D1062996S

(12) **United States Design Patent** (10) **Patent No.:** **US D1,062,996 S**
(45) **Date of Patent:** **** Feb. 18, 2025**

(54) **ELECTRIC SPRAYER**

(71) Applicant: **Jianfei Yang**, Guangdong (CN)

(72) Inventor: **Jianfei Yang**, Guangdong (CN)

(**) Term: **15 Years**

(21) Appl. No.: **29/965,187**

(22) Filed: **Sep. 26, 2024**

(30) **Foreign Application Priority Data**

Sep. 6, 2024 (CN) 202430571653.X

(51) **LOC (15) Cl.** **23-01**

Primary Examiner — Keith J Wilson

(57) **CLAIM**

The ornamental design for an electric sprayer, as shown and described.

DESCRIPTION

FIG. 1 is a front perspective view of an electric sprayer showing my new design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken lines in the drawings depict portions of the electric sprayer and form no part of the claimed design.

1 Claim, 7 Drawing Sheets
